UNITED STATES PATENT OFFICE

2,199,873

OIL WELL RIG

Mervin E. Bolles, Oil City, Pa.

Application October 3, 1938, Serial No. 233,079

17 Claims. (Cl. 255—11)

The present invention relates to drilling rigs for oil wells and has for its primary object to provide a motor driven friction drive means arranged for selective driving engagement with the double band wheels which supply the motion to the walking beam or with the double bull wheels on which the drilling cable is wound.

A further important object of the invention is to provide a sand reel mounted for movement into and out of operative engagement with the friction drive means.

A still further important object is to provide a hydraulic feed adapted for raising or lowering the tools in the well in place of the conventional type of temper screw ordinarily employed for this purpose.

Another object is to provide indicating means arranged to show the extent of movement of the hydraulic feed.

20 A further object is to provide a portable oil well rig of this character which includes a power plant arranged for driving the friction operating means for the bull wheel as well as the band wheel and also including means for supplying fluid under pressure for operating the hydraulic feed.

It is also an object of the present invention to provide automatic brake means for the bull wheel, the band wheel and the sand reel which are arranged in braking position when out of driving engagement.

30 A still further object is to provide an apparatus of this character of simple and practical construction, which is efficient and reliable in performance, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which.

Figure 1 is a side elevational view showing one side of the machine.

45 Figure 2 is a similar view showing the opposite side thereof.

Figure 3 is a top plan view with parts broken away and shown in section.

Figure 4 is a detail of the mounting for the pair of friction drive wheels.

50 Figure 5 is an end elevational view thereof, with parts broken away and shown in section.

Figure 6 is a top plan view of the cam for shifting the friction drive wheels into their respective operating positions.

Figure 7 is a detail of the stop arm for the shaft of the friction drive wheel.

Figure 8 is a top plan view of the hydraulic feed, with parts broken away and shown in section.

Figure 9 is a longitudinal sectional view of the cross head for the hydraulic plunger, taken substantially on a line 9—9 of Figure 10.

Figure 10 is a transverse sectional view of the cross head, taken substantially on a line 10—10 of Figure 8.

Figure 11 is a detail of the control valve for the hydraulic feed.

Figure 12 is a fragmentary front elevational view of the indicator for the hydraulic feed.

Figure 13 is a detail of the cross beam connecting the ends of the cable for the hydraulic feed with the clamp for the drilling cable.

Figure 14 is a detail of the loose connection between the brake of the band wheel and the friction drive control means.

Figure 15 is a detail showing the movable drive connection for the sand reel, and

Figure 16 is a diagram of the fluid pressure means for the hydraulic feed.

Referring now to the drawings in detail, the numeral 5 designates a chassis frame supported on wheels 6, the frame providing a support for a power plant 7 as well as a pair of upstanding posts 8 positioned at opposite sides of the frame 30 and having a walking beam 9 pivoted as at 10 on the upper portion of said post. Rising from the chassis are also a plurality of upstanding frame members 11 supporting an upper horizontal frame member 12 at the upper portion thereof. The 35 chassis also includes a laterally projecting frame member 13, all of said frame structure providing a support for the operating mechanism to be presently described.

Journalized on the frame is a transversely extending shaft 14 adjacent each end of which is keyed a band wheel 15 and to each of which a pitman 16 is eccentrically connected at one end for driving the walking beam 9.

Journalized in the post 8 is a transversely extending shaft 17 having at each end thereof a bull wheel 18, said bull wheel being connected by a drum 19.

The power plant 7 operates a telescopic drive shaft 20 for driving a pair of friction wheels 21 through a suitable gear connection (not shown) contained within a housing 22 and from which laterally extending shaft housings 23 extend at opposite sides and upon the opposite ends of which the wheels 21 are supported as clearly illus-

trated in Figures 5 and 16 of the drawings. The wheels 21 may be of any suitable type, such as pneumatic or solid rubber tires, or of any other suitable friction material such as leather or the like and are positioned between the adjacent band wheels 15 and bull wheels 18 at the respective sides of the apparatus for selective friction gripping engagement with either the bull wheel or the band wheel.

10 The housings 23 are supported on the upper ends of posts 24 through a ball and socket connection 25 at the upper ends of the posts, one of the posts being positioned adjacent each end of the housing, the lower end of the post being 15 connected to a transversely extending rock shaft 26 journaled in bearing brackets 27 secured to the chassis 5. The housing 22 is also supported upon an upright member 28 by means of a ball and socket connection 29 at its upper end, the 20 lower end of the upright member also having a ball and socket connection 30 with the chassis 5 as clearly illustrated in Figure 5 of the drawings.

Also adjacent the outer end of the housings 23 is an upstanding adjusting rod 31 having the 25 lower end thereof pivoted as at 32 to the chassis and provided with vertically spaced openings 33 for selectively attaching one end of a connecting rod 34, the opposite end of the rod being secured to a plate 35 carried by the housing 23. Also 30 selectively secured to one of the openings 33 is one end of a rod 36, the other end of the rod being threaded and inserted through a bracket 37 and adjustably secured thereto by lock nuts 38. The bracket 37 is formed on a cam housing 39 within which a cam 40 is rotatably positioned, said cam being eccentrically mounted on a transversely extending shaft 41 journaled in brackets 42 secured to one of the upright frame members.

One end of the shaft 41 is provided with a 40 pinion gear 43 engaged by a rack 44 movable in a guide bracket 45 and to which is journaled a roller 46 engaging the upper surface of the rack to maintain the rack in engagement with the gear, as shown more clearly in Figure 1 of the drawings.

One end of the rack 44 is pivotally connected to a lever 47 pivoted as at 48 to the frame, said lever embodying a detent 49 engageable with a notched quadrant 50 to secure the wheels 21 in a neutral position as shown in Figure 1. Also 50 secured in one of the openings 33, adjacent the top of the upstanding member 31, is a brake rod 51 loosely inserted through an opening 52 in a brake operating lever 53, the rod 51 having a collar 54 adjustably secured thereon for engagement with the lever to release the brake shoe 55 from engagement with the band wheel 15. The 55 brake shoe 55 is yieldably held in brake applying position by means of a spring 56 secured to the brake lever. The brake is released upon a movement of the rod 31 and friction wheels 21 in a direction for engaging the brake wheels 15, while a disengagement of the friction wheels retracts the rod 51, thus permitting the spring 56 to apply the brake.

The bull wheel 18 is provided with a manually operated brake which includes a brake band 57 anchored at one end as at 58 and connected at its opposite end by a pivoted bell crank 59 to 70 which one end of a link 60 is pivotally attached, the other end of the link being pivotally secured to an arm 61 which has one end yieldably held by a spring structure 62 and its other end pivoted to the brake manipulating lever 63. The spring 62 is adjustably secured as at 64 to one of the

frame members and the arm 61 is arranged with respect to the lever so that the spring will hold the lever against accidental movement in either its brake applying or brake releasing position by swinging the pivoted end of the arm 61 past the 5 pivotal center of the lever when the latter is moved in either direction, as will be apparent from an inspection of Figure 1 of the drawings.

A sand reel 65, shown in detail in Figure 15 of the drawings, is journaled on frame members 66, 10 one end of the reel having a shaft extension 67 provided with a universal joint 68 and on which a floating drive wheel 69 is secured. The hub of the wheel is journaled in a bearing 70 formed intermediate the ends of a pivoted arm 71, the 15 free end of the arm being yieldably held in a raised position by a coiled spring 72 for maintaining the wheel in engagement with a fixed brake shoe 73. To the free end of the arm 71 is also secured a link 74 connected through a bell crank 20 lever 75 with a link 76 which also has a lever 77 connected thereto. The wheel 69 is positioned immediately above one of the friction drive wheels 21 and is adapted for movement into friction drive engagement therewith through the 25 manipulation of the lever 77.

In the operation of the mechanism heretofore described it will be apparent that either the pair of band wheels 15 or the bull wheel 18 may be selectively driven by the pair of friction drive 30 wheels 21 through the manipulation of the lever 47 which serves to rotate the shaft 41 through the rack 44 and pinion 43 in the desired direction, thus causing the longitudinal shifting of the pair of wheels 21 through the connection thereof with 35 the shaft 41 through the cams 40. The band wheels 15 accordingly may be driven to supply the desired motion to the walking beam 9 or the bull wheels may be driven for winding the drilling cable thereon.

A reversing mechanism for the bull wheels is also provided which comprises a wheel 78 journaled on a pivoted lever 79 and adapted for movement into a wedging position with respect to one of the bull wheels 18 and its associated friction 45 drive wheel 21, as clearly shown in Figure 1 of the drawings. The drilling cable 80 is operated through the walking beam in the usual manner and is connected thereto through a conventional cable clamping mechanism 81 suspended from a 50 cross bar 82 having a pair of cables 83 attached to the respective ends thereof. The pair of cables 83 are trained over pulleys 84 journaled at the outer end of the pair of spaced longitudinally extending arms 85 of the walking beam, the cables 55 extending toward the other end of the walking beam and are attached through connectors 86 to adjusting screws 87 secured to the opposite end of a cross head 88. The cross head is provided with a pair of spaced parallel sleeves 89 slidably 60 mounted on guides 90 suitably secured to the drill frame and intermediate the side edges of the cross head 88 is also formed a sleeve 91 slidably positioned on the reduced extension 92 of a piston 93.

Also mounted on the reduced extension 92 at the front and rear sides of the cross head 88 are coiled springs 94, one end of each of the springs being suitably anchored to the piston 93.

The piston 93 has a working fit in a cylinder 95 70 secured to the drilling rig frame, the end of the cylinder remote from the piston having an oil pipe 96 connected thereto leading to a pump 97, the pump being driven through a shaft 98 having a friction wheel 99 secured thereto and mov- 75

able into and out of engagement with a friction drive wheel 100 mounted on the drive shaft 20. The shaft 98 is provided with a universal 101, the shaft being movable laterally by means of a lever 102 suitably connected to the shaft and to a control lever 103 through a link 104 and bell crank lever 105.

One side of the pump 97 also has an oil feed pipe 106 connected thereto leading from an oil tank 107. A pressure release pipe 108 also has one end connected to the pipe 96 and extends to the oil tank with a control valve 109 interposed therein operated by a lever 110. The pipe 96, at a point between the pump 97 and the pressure release pipe 108 also has a check valve 111 therein.

To the pipe 96, immediately adjacent the cylinder 95, is also connected a reservoir 112, arranged in an upright position and having an air chamber 113 in its upper portion which acts as an air cushion and cooperates with the springs 94 to prevent jarring of the piston 93 upon release of the pressure.

Adjacent the end of the cylinder 95, opposite from the pipe 96 is connected one end of a pipe 114 also leading to the oil tank 107 and which serves as a return line from the cylinder to the oil tank to prevent the pump 97 from creating excess pressure in the cylinder which would cause the projection of the piston 93 beyond the connection of the return pipe 114.

Connected to the piston 93, adjacent its outer end, is one end of a wire cable 115 which extends toward the opposite end of the machine adjacent the oil pump control lever 103 and the pressure release lever 110 and has its opposite end attached to an indicator 116 movable along a scale 117 secured to the frame of the machine whereby to indicate the extent of movement of the piston 93 and as a consequence, to indicate to the operator the extent of raising or lowering movement of the cable 80. A weight 118 is also attached to the wire 115 to take up slack therein.

In the operation of the hydraulic feed in order to raise the feed or drill bit, the operator moves the friction drive wheel 99 into operative engagement through the lever 103 causing the pump to move the piston 93 outwardly to raise the drill bit the desired amount. Likewise the feed may be lowered any desired amount by opening the bleed valve 109.

The double walking beam construction is of particular advantage in that it enables the pulling and baling between the beam without interference thereby. The walking beams are also provided with the usual spudding wheels 119.

The other end of the shaft is provided with a lateral arm 41' adapted for swinging with the shaft into upper and lower positions as shown by the dotted lines in Figure 7, into engagement with one of the frame members to limit movement of the shaft. Adjustable screws 41'' are carried by the frame to regulate the stopping position of the arm.

Having thus described the invention, what I claim is—

1. A drilling rig comprising an engine drive shaft, a bull wheel and a band wheel and pneumatic friction drive means having driving connection with the drive shaft and mounted for bodily movement independently of the drive shaft for selective engagement with said wheels.

2. A drilling rig comprising a power plant, a bull wheel and a band wheel and a floating friction drive wheel having telescoping drive shaft

engagement with the power plant for selective movement into operating engagement with said wheels.

3. A drilling rig comprising a bull wheel and a band wheel, friction drive means selectively engageable therewith and brake means for one of the wheels automatically actuated into brake applying position by the disengaging movement of the friction drive means with said one wheel.

4. A drilling rig comprising an engine drive shaft, a pair of driven bull wheels, a pair of driven band wheels and a pair of friction drive wheels having telescoping drive shaft engagement with the drive shaft and mounted for simultaneous bodily movement into operative engagement with one pair of said driven wheels.

5. A drilling rig comprising an engine drive shaft, a pair of bull wheels, a pair of band wheels, a pair of floating friction drive wheels having telescoping drive shaft engagement with the drive shaft and means for selectively moving said drive wheels into and out of driving engagement with the respective bull and band wheels.

6. A drilling rig comprising an engine drive shaft, a pair of bull wheels, a pair of band wheels, brakes for said wheels, a pair of pneumatic friction drive wheels having telescoping drive shaft engagement with the drive shaft and movable into and out of driving engagement with the respective pairs of bull and band wheels and brake applying means for one of said wheels normally maintained in braking position and released by the movement of the drive wheels into driving engagement with said one pair of wheels.

7. A drilling rig comprising a pair of bull wheels, a pair of band wheels, a pair of swingably mounted pneumatic friction drive wheels adapted for selective engagement with said bull and band wheels and an engine drive shaft operatively connected to the friction drive wheels, said drive wheels being movable longitudinally with respect to said shaft.

8. A drilling rig comprising a pair of bull wheels, a pair of band wheels, a pair of pneumatic friction drive wheels and a swingable mounting for the drive wheels for selectively moving the same into engagement with the bull and band wheels and comprising a horizontal rock shaft and supports rising from the rock shaft, said drive wheels being swivelly mounted on the upper ends of said supports.

9. A drilling rig comprising a pair of bull wheels, a pair of band wheels, a sand reel and pneumatic friction drive means for said bull and band wheels and said reel, said drive means being selectively movable into driving engagement with the bull and band wheels and said sand reel including a friction drive wheel having bodily movement independent of the reel and being movable into operating engagement with the drive means.

10. A drilling rig comprising a pair of bull wheels, a pair of band wheels, a sand reel and pneumatic friction drive means for said bull and band wheels and said reel, said drive means being selectively movable into driving engagement with the bull and band wheels and said sand reel including a friction drive wheel having bodily movement independent of the reel and being movable into operating engagement with the drive means, and brake means for said wheels and reel and normally retained in braking position.

11. In a hydraulic feed for drilling rigs comprising a cylinder having a fluid pressure feed

line attached thereto, a piston having a working fit in the cylinder, a cross-head on the outer end of the piston, and spring checks carried by the piston and engaging opposite ends of the cross-head.

5. 12. In a hydraulic feed for drilling rigs comprising a cylinder having a fluid pressure feed line attached thereto, a piston having a working fit in the cylinder, a confined fluid, a reservoir, a pump adapted to force the fluid under pressure to one end of the cylinder and a pressure release line connecting the cylinder adjacent its other end to the reservoir and adapted to provide an open circuit for the fluid between the pump and the reservoir upon a predetermined pressure operated movement of the piston.
10. 13. A drilling rig comprising a pair of bull wheels and a pair of band wheels mounted on parallel shafts, a pair of pneumatic friction drive wheels rockably mounted between said bull and band wheels and adapted for selective engagement with one pair of said wheels, a power plant, and a drive shaft extending in a direction toward the friction wheels and operatively connecting said wheels with the power plant.
15. 14. A drilling rig comprising a pair of bull wheel and a pair of band wheels mounted on parallel shafts, a pair of friction drive wheels rockably mounted between said bull and band wheels and adapted for selective engagement

with one pair of said wheels, a power plant, and a telescoping drive shaft forming a direct driving connection between the friction wheels and the power plant.

15. A drilling rig comprising a bull wheel and 5 a band wheel, a swingably supported power driven friction drive wheel having pneumatic tires mounted thereon and means for moving the friction drive wheel into and out of driving engagement with the respective bull and band wheels 10 and comprising a rotatable shaft, an eccentric mounted thereon and means connecting the eccentric to the support of the friction drive wheel.

16. A drilling rig comprising a pair of bull wheels and a pair of band wheels, said pairs of 15 wheels being arranged on parallel shafts, a pair of wheels having pneumatic tread surfaces and movably mounted for frictionally engaging the bull and band wheels and means for driving said pneumatic wheels.

20. 17. A drilling rig comprising a pair of bull wheels and a pair of band wheels, said pairs of wheels being arranged on parallel shafts, a pair of wheels having pneumatic tread surfaces and movably mounted for frictionally engaging the 25 bull and band wheels and means for continuously driving said last named wheels during engagement or disengagement thereof.

MERVIN E. BOLLES. 30
